UNITED STATES PATENT OFFICE.

NOEL H. LYSONS, OF MONTREAL, QUEBEC, CANADA, ASSIGNOR TO WESTERN ELECTRIC COMPANY, INCORPORATED, OF NEW YORK, N. Y., A CORPORATION OF NEW YORK.

CALLING DEVICE.

Application filed May 24, 1922. Serial No. 563,185.

To all whom it may concern:

Be it known that I, NOEL H. LYSONS, a subject of the King of England, residing at Montreal, Province of Quebec, Canada, have invented certain new and useful Improvements in Calling Devices, of which the following is a full, clear, concise, and exact description.

This invention relates to calling devices and particularly to impulse transmitters employed in automatic and semi-automatic telephone systems for the purpose of controlling the operation of switching mechanism.

In automatic telephone systems it is necessary to allow a certain minimum time interval between the last impulse of a series sent by a calling device and the first impulse of the next series in order to permit the switching mechanism to distinguish between successive digits. This interval must be of as long a duration as the maximum time required for the automatic hunting operation of the switches at the central office. In the usual type of calling device, a period of delay, after the group of impulses for each digit is sent, is secured by reason of the necessity of resetting the device for the next digit. It has been found by experience, however, that this period is not always sufficient, particularly when the resetting movement is small, as in the case of the lower digits.

The object of the invention is to provide an impulse transmitter with simple and efficient means for insuring the proper time interval between the transmission of successive series of impulses in order to prevent false connections from being made.

The invention provides means, such as an arm integral with the motor spring and controlled by the main shaft of the dial, for removing the impulse springs from the control of the interrupter mechanism after the required number of impulses has been transmitted and at a definite time interval before the mechanism reaches its normal position.

In the drawing, Fig. 1 is a front view of a calling device embodying the invention;

Fig. 2 is a rear view;

Fig. 3 is a side view;

Figs. 4 to 8, inclusive, show in successive

stages, the operation of the impulse springs of the calling device; and

Fig. 9 shows a modified arrangement of springs in a position corresponding to Fig. 4; and

Fig. 10 is a fragmentary view of a detail of the device.

The dial plate or finger wheel 1 is fixed to a shaft 2 rotatably supported in a base plate 24. A spring 25 serves as a motor spring for driving the shaft. On the under side of the dial plate 1 is secured a pawl 27 which is arranged to engage with the ratchet 28 carried by the gear member 5, which meshes with the pinion 6. On the same shaft as the pinion 6 is the butterfly cam or interrupter 3 and the gear 7, the latter of which drives the governor 4. The relation of the pawl and ratchet 27 and 28 is such that when the finger wheel is revolved in a clockwise direction, referring to Fig. 1, the gear 5 is not rotated. When the finger wheel is subsequently released, it is returned to its normal position by means of the motor spring 25, and during its return movement, the pawl 27 engages ratchet 28 and, therefore, causes the rotation of the interrupter 3 and the governor 4, all as disclosed more in detail in U. S. Patent No. 1,279,352 of September 17, 1918, to A. E. Keith.

On the interrupter cam shaft is secured a collar 30 having two diametrically disposed notches or recesses 31; mounted on the plate 24 is a bent leaf spring 32 with its free end arranged to engage one of the notches 31 when the interrupter cam is in normal position; the position of the spring is such that when the cam 3 and collar 30 rotate in a counter-clockwise direction (as viewed in Fig. 2), the spring 32 is depressed and the collar 30 rides over it, and if there is a tendency to rotate in the opposite direction, the side wall of one of the recesses 31 meets the end of the spring 32 and further movement is prevented.

Contact spring set 10, mounted on the rear of the base plate 24, comprises the springs 11, 14, 15, and 16. The arrangement of the springs is such that spring 14 tends to move toward spring 16 and makes contact

therewith, and impulse spring 11 tends to move away from spring 15 and to bring its end 12 into the path of rotation of interrupter 3. However, when the finger wheel 5 1 is in normal position, as shown in Fig. 1, finger 13 carried on the inner end of the shaft 2, bears upon the upper surface 14' near the free end of the spring 16 and holds it away from spring 16 and against spring 10 11, which in turn is held against spring 15, making contact therewith and holding its outer end 12 out of the path of the interrupter 3. The arm 13, in the form shown 15 in the drawings, is an insulated extension of the motor spring 25.

In practice, the contact spring 15 will be connected by a suitable conductor 44 to one side of the subscriber's line, while the springs 11 and 14, which are tied together, 20 will be conductively connected to the other side 40 through the subscriber's receiver 41 and transmitter 42. Spring 16 will be conductively connected to the second side 40 of the subscriber's line in shunt of the receiver 25 41. Therefore, when the springs are in the position shown in Figs. 4 and 8 of the drawing, the circuit will be closed through the subscriber's telephone instruments.

When the subscriber dials the first digit 30 by rotating the finger wheel in a clockwise direction, the arm 13 will be moved in the direction of the arrow, in Fig. 4, and will, therefore, after a short movement, release the spring 14, which will thereupon rise 35 and make contact with spring 16, thereby shunting the subscriber's receiver during the dialing operation, as is common practice. The release of spring 14 also results in the partial release of spring 11. Spring 11, 40 however, is permitted to move only a short distance when it is stopped by the contact of its outer end 12 with a wing of the interrupter 3. This movement of spring 11 is not sufficient to break its contact with 45 spring 15. As soon as the finger wheel is released and starts on its return movement, the interrupter 3 is rotated as described above and intermittently releases and depresses the spring 11, (Figs. 6 and 7) thus 50 alternately breaking and making its contact with spring 15 and, therefore, sending out impulses over the line and effecting the selective operation of a switching device at 55 the central exchange in a well-known manner.

Since it is the custom of the calling subscriber to immediately reset the dial, the second series of impulses is frequently begun before connection has been completed 60 at the central exchange to a switch that is free to respond to its impulses, with the result that there is an incorrect setting of the switches. In the present device, the dial plate 1, and therefore the interrupter 3, continue to rotate for a substantial period, 65

when the required number of impulses has been transmitted over the line and after the dial is brought to such a position that the member 13 is in the position shown in Fig. 7 and moving in the direction of the arrow. 70 Spring 14 is, therefore, depressed, breaks its contact with the spring 16, depresses the spring 11, and holds the latter spring in contact with spring 15 so that contact is maintained during the entire rotation of the interrupter 3 and no impulses are sent over the line. As the dial continues to rotate, 75 arm 13 moves in the direction of the arrows shown in Figs. 7 and 8, and finally when the dial plate reaches its normal relation, 80 the parts assume the position shown in Fig. 8, which is the same as that shown in Fig. 4. The dial will now be reset for the next series of impulses and the sequence of operations shown in Figs. 4 to 8 will be repeated. 85 There is, thus, added to the interval required for resetting the dial an interval equal to the time which is occupied by the dial in moving through an angle sufficient to bring the interrupter 3 to the position 90 shown in Fig. 8. The length of this period will depend upon the length of bearing surface 14' of the spring 14. A period equivalent to that required for sending two impulses has been found to give satisfactory 95 results.

The modification shown in Fig. 9 is adapted to be used with a circuit similar to that shown in U. S. Patent No. 1,353,612, 100 September 21, 1920, to F. N. Reeves. Spring 15 will be connected to one side 43 of the line. Spring 20 will be connected through the receiver 49 to the same side of the line. Springs 11 and 16, which are electrically tied together, will be connected to the other side 45 of the line through the transmitter 46. Spring 14 will be connected to said other side 45 of the line in shunt of the transmitter 46 when the substation circuit is ready for the calling device to be 105 operated. Spring 16 is adapted to cooperate with spring 14 to close a path alternate to the path through spring 20 and the receiver. Spring 11 is provided with an insulated member 22 to prevent electrical connection between it and spring 14. 110

What is claimed is:

1. In an impulse sending device, a finger wheel for setting said device, contact springs, an interrupter for said contact springs, a motor spring for operating said device, and means integral with said motor spring for removing said contact springs from the control of said interrupter. 120
2. In an impulse sending device, a finger wheel for setting said device, a plurality of contact springs, an interrupter in operative relation to one of said contact springs, a motor spring, an arm integral with said motor spring in operative relation to an- 125
3. In an impulse sending device, a finger wheel for setting said device, a plurality of contact springs, an interrupter in operative relation to one of said contact springs, a motor spring, an arm integral with said motor spring in operative relation to an- 130

other of said contact springs and controlled by said finger wheel for removing said springs from the control of said interrupter.

3. In an impulse sending device, a finger wheel for setting said device, a plurality of contact springs, an interrupter in operative relation to one of said contact springs, a motor spring, an arm integral with said

motor spring in operative relation to another of said contact springs and controlled by said finger wheel for removing said springs from the control of said interrupter. 10

In witness whereof, I hereunto subscribe my name this seventeenth day of May, A. D. 1922.

NOEL H. LYSONS.
